UNITED STATES PATENT OFFICE

2,485,491

RECIPROCATING VANE PUMP

Ray G. Holt, Euclid, Ohio, assignor, by mesne assignments, to Borg-Warner Corporation, Chicago, Ill., a corporation of Illinois

Application August 30, 1943, Serial No. 500,519

2 Claims. (Cl. 103—136)

1

This invention relates to pumps of the radially reciprocable vane type and has as the general object thereof the provision of an improved arrangement of vanes, supporting rotor, eccentrically embracing sleeve and center pin for controlling the radially inner terminal of the vanes and maintaining the outer terminal portion thereof in contact with the surrounding sleeve.

I am aware that springs have been proposed for urging the vanes radially outwardly into engagement with the embracing sleeve or housing but I am not aware of any previous construction incorporating the improved feature of my arrangement.

It is a particular object of my invention to provide in combination a new center pin construction having an improved mode of operation and coaction with the vanes controlled thereby.

Other and more particular objects, advantages and uses of my invention will become apparent from a reading of the following specification taken in connection with the accompanying drawings forming a part thereof and wherein:

Fig. 1 is a broken-away cross sectional view taken substantially on line 1—1 of Fig. 2 and showing one preferred embodiment;

Fig. 2 is a broken-away axial sectional view taken substantially on the line 2—2 of Fig. 1;

Fig. 3 is a broken-away cross sectional view showing a second alternative arrangement;

Fig. 4 is a broken-away axial sectional view of the arrangement shown in Fig. 3; and

Fig. 5 is a broken-away, sectional view showing a third alternative arrangement.

Referring now in greater detail to the figures of the drawing, one preferred embodiment is illustrated in Figs. 1 and 2 and includes essentially a housing indicated generally at 10 formed with a cylindrical bore 12 and ports 14 and 16 either of which ports may become selectively the inlet or the outlet port depending upon the direction of operation of the fluid displacement device as well as whether the same is being operated as a pump or as a motor. Bore 12 preferably has inserted therein a liner or sleeve 18, formed of a suitable wear-resistant metal such as bronze or steel. This liner 18 is formed with ports 20 and 22 for cooperation respectively with ports 14 and 16 in the housing 10. Received within sleeve 18 is the center portion of a rotor 24 eccentrically positioned with reference to the sleeve and having journals 26 and 28 received in reduced bores 32 and 34 on either side of main bore 12 for rotation therein about a fixed axis.

Rotor 24 is formed with a plurality of radially

2

extending slots 36 in which are mounted for radial reciprocation a corresponding plurality of vanes 38 the outer terminal portions of which engage the inner periphery of the sleeve 18 while the radial inner terminals thereof are adapted to be engaged and controlled by a specially constructed roller-like center pin 40.

It is to the special construction of this center pin 40 and the novel mode of coaction thereof in combination that my invention is especially directed.

In this preferred embodiment roller-like center pin 40 is in the form of a coiled strip of spring steel with the ends thereof spaced apart to provide a small free joint opening and give the desired value of radially outward pressure against the inner end of blades 38. One end of this coiled strip is defined by a pair of inwardly converging portions 42 and 44 while the opposed end is defined by a complementary pair of outwardly diverging portions 46 and 48 thus forming a free joint wherein the terminal portions of the spring strip always present a bearing surface for the inner ends of the vanes in effecting the transition of the vanes across the free joint opening from one end of the spring roller to the other.

Spring roller-like center pin 40 engages each of the vanes 38 throughout the axial extent thereof applying radially outward pressure therefor to maintain the requisite sealing engagement of the outer ends of the vanes with the surrounding sleeve 18. This is effective to take up for the wear occurring between the elements as well as rendering practicable a more liberal tolerance upon initial installation. The center pin 40 is also preferably made with sufficient strength to normally prevent any inward radial compression thereof by the action of the vanes in the rotation of the vanes in contact with the bore. Coupling connection 50 may be employed for transmitting torque to the rotor 24 in the event that the assembly is to be operated as a pump or alternatively for the purpose of transmitting power from the assembly in the event the same is to be operated as a fluid motor.

Turning now to Figs. 3 and 4 there is illustrated still another form of roller-like resilient center pin construction indicated generally at 140. In this modification the center pin 140 is made of rubber or rubber-like material such as a synthetic composition. In other respects this center pin is similar in function and mode of operation to that above described.

Referring to Fig. 5, this modification differs from the above forms in the use of a helical

coiled spring 248 as the resilient center pin. This spring is preferably ground to provide a substantially continuous flat peripheral surface 241 effective to engage the inner terminal portions of the vanes or blades 38 substantially throughout the axial extent thereof.

While I have disclosed only those parts of a fluid displacement device essential to cooperation in the present combination, it is to be understood that in an actual installation all of the conventional elements necessary will be provided. It will also be noted that while I disclose and describe the provision of a wear-resistant liner 18 it is contemplated that the outer ends of vanes 38 may operate in direct contact with a bore formed in the housing where no such liner is to be provided, and where the word "bore" is employed in the claims both arrangements are contemplated.

From the above it will appear that I have provided a resilient preloaded center pin or roller arrangement in combination with an eccentric rotor type of fluid displacement device, which center pin or roller while not subject to appreciable radially inward compression, nevertheless functions to maintain the vanes in sealed engagement with the surrounding cylindrical housing bore. This has the advantage among other things of making it unnecessary to observe the close tolerances in manufacture that are normally required in the absence of this resilient center pin construction. It will be noted that the present resilient center pin construction is quite distinguishable from the previously known resilient means employed in pumps of the opposed rotary vane type having irregular or cam-shaped bores. In these former arrangements the cams formed in the bore are effective during certain portions of the arcuate movement to move opposed vanes or blades radially in the direction of one another and hence employ, for example, coil compression springs for subsequently urging the vanes radially apart. The present invention is clearly distinguishable in that the substantially circular cross section of the cylindrical bore employed results in appreciably no relative radial movement of opposed vanes with respect to one another. The herein disclosed resilient roller arrangement has the marked advantage that a predetermined or substantially select loading of the resilient rotor may be employed and there is no requirement that an excess loading be provided for during rotation as is the case with irregular bore contour type of fluid displacement devices.

Therefore, I am aware of no previous application or appreciation of the use of an elongated, resilient, roller-like center pin in combination with an eccentric rotor reciprocable vane type of fluid displacement device and incorporating the advantages herein disclosed.

While I have disclosed my invention in con-

nnection with certain specific embodiments thereof it is to be understood that these are by way of example rather than limitation and that my invention should be defined by the appended claims.

I claim:

1. In a rotary fluid displacement device including means defining a cylindrical bore having fluid inlet and outlet ports communicating therewith, a rotor positioned eccentrically within said bore for rotation therein, radially reciprocable elongated vanes carried by said rotor and means defining an elongated roller-like resilient center pin engaging the radial inner terminals of said vanes and maintaining the radial outer terminals thereof in sealing engagement with said cylindrical bore, said means comprising a helically coiled spring, said coiled spring having a ground peripheral surface effective to increase the area of contact between successive turns and the radial inner terminals of the respective vanes.
2. In a rotary fluid displacement device including a housing formed with a cylindrical bore and having fluid inlet and outlet ports communicating with said bore, a rotor positioned eccentrically within said bore for rotation therein, radially reciprocable elongated vanes carried by said rotor and means defining an elongated roller-like resilient center pin contacting the inner radial extremities of said vanes and overlapping said vanes axially at both axial extremities of said vanes and functioning to maintain the outer radial terminals of said vanes in sealing engagement with said cylindrical bore, said resilient center pin consisting of a helically coiled spring, the peripheral surfaces of each turn being generated by a straight chordal line having an axial dimension less than the diameter of said coil spring whereby to provide a greater area of contact between said coil and said vanes than would be provided by a spring of circular cross-section but less area of contact than would be provided by a solid center pin.
